DESIGN FOR A PLATE

Charles W. Carlson, Tiffin, Ohio, assignor to
United States Glass Company, Tiffin, Ohio, a
corporation of Pennsylvania

Application November 8, 1944, Serial No. 116,218

Term of patent 14 years

(Cl. D44—15)

To all whom it may concern:

Be it known that I, Charles W. Carlson, a citizen of the United States, residing at Tiffin, in the county of Seneca and State of Ohio, have invented a new, original, and ornamental Design for a Plate, of which the following is a specification, reference being had to the accompanying drawing, forming a part thereof.

Fig. 1 is a plan view of my plate; and
Fig. 2 is a cross-section thereof with portions of the ornamentation omitted for illustrative purposes.

I claim:
The ornamental design for a plate, as shown.

CHARLES W. CARLSON.
